UNITED STATES PATENT OFFICE.

EDWARD CRAIG, OF ST. JOSEPH, MICHIGAN, ASSIGNOR, BY MESNE ASSIGNMENTS, TO SARANAC MACHINE CO., OF ST. JOSEPH, MICHIGAN, A CORPORATION OF MICHIGAN.

AUTOMATIC CARTON-MACHINE.

1,161,033.

Specification of Letters Patent. Patented Nov. 23, 1915.

Application filed July 1, 1909. Serial No. 505,490.

To all whom it may concern:

Be it known that I, EDWARD CRAIG, a citizen of the United States of America, and resident of St. Joseph, Berrien county, 5 Michigan, have invented a certain new and useful Improvement in Automatic Carton-Machines, of which the following is a specification.

My invention relates to machinery for 10 making cartons or boxes.

It relates more particularly to machinery for making square or rectangular boxes which are each provided with a folding cover. Cartons or boxes of this kind are ordinarily 15 made of paste-board, which material is folded to provide a carton or box having straight sides and ends, a flat bottom, and a cover flexibly secured to the upper edge of one of the side walls. The side walls have flaps 20 which are folded upon the surfaces of the end walls. Cartons or boxes of this particular character are used for various purposes and are very popular.

The object of my invention is to provide 25 a machine which will receive the sheet of cardboard in blank form and fold and staple the same to produce a carton or box of this particular character. It contemplates a machine having a hopper in which 30 the blanks are held, and from which the same are fed automatically to the forming and stapling devices, whereby each blank is automatically folded and then stapled together to provide a carton or box of the desired shape and character. More broadly 35 considered, it contemplates a machine which will automatically fold and secure the sheet material together, thereby providing a carton or box having sides and ends extending 40 at right angles to each other, as well as at right angles to the bottom, and an integral cover in the plane of one side wall. The nature of my invention will, however, hereinafter more fully appear.

45 It is also an object to provide certain novel features of construction and details and combinations which, either separately or together, will tend to increase the general efficiency of a carton machine of this or 50 similar character.

In the accompanying drawings:—Figure 1 is a rear elevation of an automatic carton or box machine embodying the principles of my invention. Fig. 2 is a front elevation of 55 the said machine. Fig. 3 is a side elevation

of the said machine. Fig. 4 is a vertical section on line 4—4 in Fig. 1. Fig. 5 is a plan of the machine shown in Fig. 1. Fig. 6 is a detail perspective of the mechanism for regulating the automatic feed of the 60 blanks from the hopper. Fig. 7 is a detail sectional view of the folding mechanism, the section being taken on line 7—7 in Fig. 4. Figs. 8 and 9 are enlarged detail views of the automatic knock-out device—that is to 65 say, the device for ejecting the finished carton from the machine. Fig. 10 is a fragmentary or detail perspective view of the mechanism for folding the blanks. Fig. 11 is a perspective of one of the strippers for releasing the finished carton from the plunger when the latter moves downward. Fig. 12 is an enlarged detail sectional view of the reciprocating table and the stationary support upon which the same rests. Figs. 13 70 and 14 are detail views of certain devices for assisting in the folding of the end walls of the carton. Fig. 15 is a perspective of the blank from which the carton is made. Fig. 16 is a perspective of the finished carton. Fig. 17 is a side elevation of the plunger and form shown in Fig. 7. Fig. 18 75 shows a form of box or carton requiring two staples for each end. Fig. 19 shows a box or carton of such form that the flaps do not lap. Fig. 20 shows a form of box or carton in which the flaps are inside of the end walls.

As thus illustrated, my invention comprises a frame or body A adapted to support the various operative parts in suitably elevated positions. At its top the said frame is provided with a horizontal support a upon which rests a reciprocating table B, which latter is provided on its upper surface with teeth b. These teeth are adapted to engage the edges of the blanks to feed them forward. The said reciprocating table is operated by a lever b' connected therewith by links b², and having its lower end pivoted at b³. This lever b' is operated by a cam b⁴ connected therewith by means of a strap b⁵, which cam is carried on the drive shaft C. The hopper D is disposed over the said reciprocating table, and is adapted to receive the blank E, shown in Fig. 15, and shown more clearly by Fig. 5. The said blank consists of a bottom e, side walls e', end walls e², and end flaps e³, e⁴, together with a cover e⁵ integral with the upper edge of one 100 105 110

of the side walls. When the blanks are placed in the hopper, it will be seen that the covers e^5 extend forward in the direction in which the blanks are to be fed. Each blank when fed forward rides over an inclined stationary member b^6 , so that the forward edge of the central portion of each blank is caused to bend slightly upwardly, as shown in Fig. 6. This upwardly displaced portion of the blank is then caused to pass under a finger b^7 , which latter projects downwardly very close to the top of the member b^6 , there being just room for a single blank to pass. Consequently, if two or more blanks have been accidentally fed forward by the reciprocating table, only one blank can then pass between the member b^6 and the finger b^7 , as the space between the two will not admit more than one blank. The blank thus fed forward is then seized by a pair of feed rolls b^8 which are operated by a sprocket chain connection b^9 , as shown in Fig. 3. This sprocket chain leads to a sprocket b^{10} on the shaft b^{11} , which latter has a gear connection b^{12} with the shaft C, as shown in Fig. 1. In this way the blanks are automatically fed forward to the forming and stapling mechanisms, which latter are as follows: The folding and forming mechanisms comprise a vertically disposed plunger F, which is rectangular in shape, and thereby adapted to fit the interior of the square corner carton. The lower end of this plunger has a link f that connects it with a strap f' which is operated by the cam f², and which has its rear end pivoted at f³ to the upper end of a link f⁴, which latter has its lower end pivoted at f⁵. Rotation of the cam f² causes the plunger F to move up and down in its housing or bearing f⁶. The said housing carries the upper strippers f⁷ which are adapted to engage the edges of the ends of the carton, when the latter is finished, thereby disengaging the finished carton from the plunger. The lower strippers f⁸ serve to engage the lower edge of the cover of the carton, thereby assisting in lifting the same off from the plunger. The strippers f⁷ are joined at the back of the plunger to form a back stripper f⁹, which latter engages the lower edge of the side of the carton. The housing for the plunger is provided with a pivoted finger or knock-out device f¹⁰, which latter is normally pressed against the plunger by a spring f¹¹, as shown in Fig. 8. The plunger has a slot or groove f¹² on its face into which the said finger or knock-out device f¹⁰ is adapted to slide when the plunger moves downward. The said plunger is also provided with cams f¹³ adapted to engage rolls f¹⁴ on the finger f¹⁰, whereby the latter is caused to move outwardly when the plunger moves down, as shown in Fig. 9. This throws the carton out of the machine, as the cover of the car-

ton slides down over the finger f¹⁰. When the carton is stripped from the plunger, then the outward movement of the finger f¹⁰ against the inner surface of the cover throws the carton out of the machine. The cams f¹³ 70 on the face of the plunger, and at each side of the groove or slot f¹², serve to deflect the cover outwardly and over the finger or knock-out device f¹⁰ when the plunger moves downward.

Above the plunger is a stationary form G having downwardly projecting and outwardly extending folders g at each side thereof. These folders engage the side walls e' to fold the same downward when the plunger moves upward. The upper portion of said folders g are vertical and parallel, being in the form of side walls, and slide on the side of the carton during the upward movement of the latter. This sliding action also occurs when the carton moves downward after being formed, as formerly explained. The ends of the blank are fed into channels g' disposed at opposite ends of the form. It will be seen that the central portion of each channel is slightly depressed, so that the overhanging portions g² will cause the end walls e² of the blank to be depressed considerably below the flaps e³, e⁴, which latter will rest upon the shoulders g⁵. The blanks are fed into these channels g' by the feed rolls b⁸, and the motion in this direction is limited by the stops g⁴ at the front of the machine. When the plunger moves upward, the sides and ends of the blank are depressed, and the shoulders g⁵ act on the flaps e³, e⁴ to depress the same, but in a plane above the end walls e². The motion continuing, the folders g⁶, one at each end of the form, and which are mounted upon the stationary frame of the machine, serve to engage the flaps e³, thus causing these flaps to fold faster than the flaps e⁴. In this way the flaps are folded one over the other upon the outer surfaces of the end walls, the flaps e³ always resting inside of the flaps e⁴, as shown in Fig. 16. The folding of the flaps upon the outer surfaces of the end walls is further insured by the end folders g⁷ which are carried by the lower end of the member g⁸, and which engage the end walls e² to fold the same quickly downwardly at right angles to the bottom e, and the flaps then fold into place on the said end walls. The said member g⁸ is co-extensive with and bears upon the bottom e, as the plunger moves upward. This member g⁸ has a vertical stem or shank g⁹ which is connected with the springs g¹⁰, whereby it is held normally in the position shown in Fig. 4. These springs, however, yield to the pressure of the plunger, so that during the folding of the blank the member g⁸ moves upward to permit the folded carton to finally come to rest within the square or rectangular form G, in the manner 130

explained, and with the cover e^5 in the vertical plane of one side wall of the square corner carton thus made. To obtain the best results, the said cover e^5 is preferably disposed at the outer side of the machine, and the folding and other devices are arranged to afford clearance for said cover, thus preventing breakage of the latter and insuring the desired results. When the blank is thus folded, it is secured in place by staples e^6 which are inserted through the flaps and end walls of the box. These staples are driven by any ordinary or suitable stapling mechanisms, such, for example, as the staplers H , which latter involve the usual staple formers and drivers, anvils and loop bars, etc. The wire for the staples is carried on reels I , and the said wire is fed to the two horizontally disposed staplers by means of the automatic feed devices J , which latter are connected for simultaneous operation by a link j , in the manner shown in Fig. 2. The said wire feeding mechanisms are operated by means of the rod or link j' which extends downward to a lever j^2 , as shown in Fig. 3. It will be seen that this lever has its rear end pivoted at j^3 , and is provided with a roll j^4 that engages a cam j^5 on the shaft C . The spring j^6 holds the lever j^2 normally downward, and when the shaft C is rotated the rod j' is reciprocated to operate the wire feeding mechanisms. The said staplers are operated by elbow or bell crank levers i which are pivoted on the frame of the machine, and which are connected by rods or pitmen i' with the lever i^2 . This lever is held normally upward by springs i^3 . (See Figs. 2 and 4.) The said lever is pivoted at its rear end at i^5 and has a pin or roll i^4 adapted to engage the groove of the cam i^5 on the shaft C . (See Fig. 4.) Thus rotation of the shaft causes the reciprocation of the rods or pitmen i' with the consequent operation of the staplers. When actuated, the staplers drive the staples e^6 through the flaps and end walls of the carton to hold the same in shape.

From the foregoing, therefore, it will be seen that I provide a machine for automatically folding and stapling blanks to produce cartons or boxes which are square or rectangular in form, having square corners, the sides and end walls of each carton or box extending at right angles to each other and at right angles to the bottom, and one side wall having an integral cover which is handled by the machine in a manner to prevent folding thereof during the making of the carton. The blanks are carried in superimposed condition in the hopper, and are automatically fed one by one from the bottom thereof, and with the cover e^5 in advance, to the forming or folding mechanism. Each blank is then automatically folded tightly upon the square or rectangular plunger, by the folding devices described, and a

single staple is then inserted in each end of the carton or box to hold the same in shape. The folding of a blank to provide a carton of this form having square corners and an integral cover involves many difficulties and problems heretofore not encountered in the production of receptacles, but by my invention these are overcome and solved in a practical manner.

For the broader purposes of my invention, I do not limit myself to the exact construction shown and described, or to the production of cartons or boxes of the exact shape and form illustrated herein. If desired, the same may be of the form shown in Fig. 18, which requires two staples for each end of the box. In Fig. 19 the flaps are outside, but do not lap. In Fig. 20 the flaps are inside. Obviously, the machine can be constructed for making these or other cartons without departing from the spirit of my invention. Also, the drawings show the illustrative machine in such position that the plunger F moves upward to make the carton; but this may be changed or modified to suit the circumstances and requirements of other cases, and, for the broader purposes of my invention, it will be understood that I do not limit myself to any particular position or direction of movement for the plunger.

What I claim as my invention is:

1. A carton machine for making a square corner carton by folding and fastening a blank having an integral cover, comprising means for feeding the blank into position for folding, automatic devices for completely folding the sides and ends of the blank at right angles to the bottom of the carton, automatic forming devices having means for folding the end flaps upon the ends, to form therewith the end walls of the carton, leaving the cover of the carton unfolded, means for inserting fastening devices through the said flaps and ends to hold the carton in shape, certain of said forming devices having means for expelling the carton after formation thereof, and means for finally detaching the carton from the machine.

2. A carton machine for making a square corner carton by folding and fastening a blank having an integral cover, comprising means for feeding the blank into position for folding, automatic devices for completely folding the sides and ends of the blank at right angles to the bottom of the carton, and to each other, automatic forming devices having means for causing the flaps which are integral with the sides to be folded upon the outer surfaces of the ends, to form therewith the end walls of the carton, leaving the cover of the carton unfolded, means for stapling the said flaps and ends together, certain of said forming devices having

means for expelling the carton after formation thereof, and means for finally detaching the carton from the machine.

3. A carton machine for making a square corner carton by folding and fastening a blank having an integral cover, comprising means for automatically feeding the blank material, automatic devices for folding the sides and ends of the blank at right angles to the bottom of the carton, automatic forming devices having means for folding the end flaps upon the ends, to form therewith the end walls of the carton, leaving the cover of the carton unfolded, means for inserting fastening devices through the said flaps and ends to hold the carton in shape, certain of said forming devices having means for expelling the carton after formation thereof, and means for finally detaching the carton from the machine.

4. A carton machine for making a square corner carton by folding and fastening a blank having an integral cover, comprising means for automatically feeding the blank material, automatic devices for folding the sides and ends of the blank at right angles to the bottom of the carton, and to each other, automatic forming devices having means for causing the flaps which are integral with the sides to be folded upon the outer surfaces of the ends, to form therewith the end walls of the carton, leaving the cover of the carton unfolded, means for inserting fastening devices through the said flaps and ends to hold the carton in shape, certain of said forming devices having means for expelling the carton after formation thereof, and means for finally detaching the carton from the machine.

5. A carton machine for making a square corner carton by folding and fastening a blank having an integral cover, comprising a hopper for holding the blanks, means for feeding the blanks from the bottom thereof, automatic devices for folding the sides and ends of the blank at right angles to the bottom of the carton, automatic forming devices having means for folding the end flaps upon the ends, to form therewith the end walls of the carton, leaving the cover of the carton unfolded, means for inserting fastening devices through the said flaps and ends to hold the carton in shape, certain of said forming devices having means for expelling the carton after formation thereof, and means for finally detaching the carton from the machine.

6. A carton machine for making a square corner carton by folding and fastening a blank having an integral cover, comprising a hopper for holding the blanks, means for feeding the blanks from the bottom thereof, automatic devices for folding the sides and ends of the blank at right angles to the bottom of the carton, and to each other, auto-

matic forming devices having means for causing the flaps which are integral with the sides to be folded upon the outer surfaces of the ends, to form therewith the end walls of the carton, leaving the cover of the carton unfolded, means for stapling the said flaps and ends together, certain of said forming devices having means for expelling the carton after formation thereof, and means for finally detaching the carton from the machine.

7. A carton machine for making a square corner carton by folding and fastening a blank having an integral cover, comprising automatic devices for folding the sides and ends of the blank at right angles to the bottom of the carton, automatic forming devices having means for folding the end flap upon the ends, to form therewith the end walls of the carton, leaving the cover of the carton unfolded, means for inserting fastening devices through the said flaps and ends to hold the carton in shape, means including a reciprocating support for the blanks to feed the same forward, certain of said forming devices having means for expelling the carton after formation thereof, and means for finally detaching the carton from the machine.

8. In a carton machine for making a square corner carton by folding and fastening a blank having an integral cover, comprising automatic devices for folding the sides and ends of the blank at right angles to the bottom of the carton, and to each other, automatic forming devices having means for causing the flaps which are integral with the sides to be folded upon the outer surfaces of the ends, to form therewith the end walls of the carton, leaving the cover of the carton unfolded, means for stapling the said flaps and ends together, means including a reciprocating support for the blanks to feed the same forward, certain of said forming devices having means for expelling the carton after formation thereof, and means for finally detaching the carton from the machine.

9. A carton machine for making a square corner carton by folding and fastening a blank having an integral cover, comprising automatic devices for folding the sides and ends of the blank at right angles to the bottom of the carton, automatic forming devices having means for folding the end flaps upon the ends, to form therewith the end walls of the carton, leaving the cover of the carton unfolded, means for inserting fastening devices through the said flaps and ends to hold the carton in shape, means including a pair of rollers for feeding the blanks forward, certain of said forming devices having means for expelling the carton after formation thereof, and means for finally detaching the carton from the machine.

10. A carton machine for making a square corner carton by folding and fastening a blank having an integral cover, comprising automatic devices for folding the sides and ends of the blank at right angles to the bottom of the carton, and to each other, automatic forming devices having means for causing the flaps which are integral with the sides to be folded upon the outer surfaces of the ends, to form therewith the end walls of the carton, leaving the cover of the carton unfolded, means for stapling the said flaps and ends together, means including a pair of rollers for feeding the blanks forward, certain of said forming devices having means for expelling the carton after formation thereof, and means for finally detaching the carton from the machine.
11. A carton machine for making a square corner carton by folding and fastening a blank having an integral cover, comprising a reciprocating table for feeding the blanks, feed rolls for taking the blanks from said table, automatic forming devices having means for folding the sides and ends of the blank at right angles to the bottom of the carton, automatic devices for folding the end flaps upon the ends, to form therewith the end walls of the carton, leaving the cover of the carton unfolded, means for inserting fastening devices through the said flaps and ends to hold the carton in shape, certain of said forming devices having means for expelling the carton after the formation thereof, and means for finally detaching the carton from the machine.
12. A carton machine for making a square corner carton by folding and fastening a blank having an integral cover, comprising a reciprocating table for feeding the blanks, feed rolls for taking the blanks from said table, automatic forming devices having means for folding the sides and ends of the blank at right angles to the bottom of the carton, and to each other, automatic devices for causing the flaps which are integral with the sides to be folded upon the outer surfaces of the ends, to form therewith the end walls of the carton, leaving the cover of the carton unfolded, means for stapling the said flaps and ends together, certain of said forming devices having means for expelling the carton after formation thereof, and means for finally detaching the carton from the machine.
13. In a machine of the class described, the combination of a plunger, a form, channels at opposite ends of the form, said channels shaped to depress the ends of the blank below the flaps which are integral with the sides of the blank, means on the form for causing the ends to fold first and the sides afterward, devices for causing one flap to fold upon the other, at each end of the blank, and means for stapling the flaps and ends together.
14. A carton machine of the class described, comprising a reciprocating plunger and form, strippers associated with the plunger, to dislodge the carton from the plunger, and an automatic knock-out operated by the motion of the plunger to expel the dislodged carton from the machine.
15. A carton machine for making a square corner carton by folding and fastening a blank having an integral cover, comprising mechanism comprising devices for folding the blank by upward motion thereof, to provide a carton having sides and ends extending at right angles to each other, and having a bottom extending at right angles to the sides and ends, leaving the cover of the carton unfolded, in combination with mechanism for inserting fastening devices only in the ends of the carton to retain the folded blank in shape.
16. In an automatic carton machine for making a square corner carton by folding and fastening a blank having an integral cover, means for folding and forming the square corner ends of the carton, leaving the cover of the carton unfolded, means for stapling the said ends, and means for feeding the stock, said machine having means for clamping the bottom of the carton during the folding operation.
17. In an automatic carton machine, means for feeding the material with a cover which is integral therewith, means for forming the material into a box, leaving the cover of the carton unfolded, and means for stapling only the ends of the box, said machine having means for clamping the bottom of the carton during the folding operation.
18. An automatic carton machine for making a square corner carton by folding and fastening a blank having an integral cover, comprising means for feeding flat sheets of material from a hopper, means for forming the same, leaving the cover of the carton unfolded and hanging downward, and means for stapling only the ends of the carton together.
19. An automatic carton machine for making a square corner carton by folding and fastening a blank having an integral cover, comprising means for feeding sheet material, means for forming the same into cartons with square corner ends, leaving the cover of the carton unfolded and hanging downward, and means for stapling only the ends of the carton, leaving the cover still open and undisturbed.
20. In a carton machine, feed mechanism for feeding the blank, an upwardly movable forming plunger, means co-operating with said plunger for preliminarily and partially

folding the blank by upward movement following the feeding motion thereof, devices for then completing the folding operation, and instrumentalities for effecting a fastening of the carton together, said means including stationary cam grooves that receive the edges of the blank.

21. A carton machine for making a square corner carton from a blank having integral bottom and side and end wall sections, and having integral flaps and a cover section integral with one side wall section,—comprising, in combination, (1) a reciprocating plunger, (2) elements coöperating with said plunger to fold the side and end walls of the blank at right angles to the bottom wall thereof, leaving said cover unfolded in the plane of one side wall, and for causing the flaps to fold at right angles to the side walls, some of said elements being stationary and others being movable during the folding operation, (3) mechanism for fastening together the flaps and end walls, after the plunger reaches the final position thereof, (4) means to clamp the bottom section against the advancing plunger, arranged for compelling the finished carton to follow said plunger when the motion thereof is reversed, (5) a device to detach the carton from the returning plunger, and (6) mechanism to move the blank edgewise into position for folding with the cover section at the outer side of the machine.

20 25 30 35 40 45 50 55 60 65 70 75 80 85 90 95 100 105 110 115 120 125

22. A carton machine for making a square corner carton from a blank having integral bottom and side and end wall sections, and having integral flaps and a cover section integral with one side wall section,—comprising, in combination, (1) a reciprocating plunger, (2) elements coöperating with said plunger to fold the side and end walls of the blank at right angles to the bottom wall thereof, leaving said cover unfolded in the plane of one side wall, and for causing the flaps to fold at right angles to the side walls, some of said elements being stationary and others being movable during the folding operation, (3) mechanism for fastening together the flaps and end walls, after the plunger reaches the final position thereof, (4) means including a reciprocating member having springs to clamp the bottom section against the advancing plunger, arranged for compelling the finished carton to follow said plunger when the motion thereof is reversed, two of said elements consisting of vertical plates arranged to hold the side sections against the plunger, said member reciprocating between the parallel inner surfaces of said plates, and (5) a device to detach the carton from the returning plunger.

23. A carton machine for making a square corner carton from a blank having integral bottom and side and end wall sections, and having integral flaps and a cover section integral with one side wall section,—comprising, in combination, (1) a reciprocating plunger, (2) elements coöperating with said plunger to fold the side and end walls of

the blank at right angles to the bottom wall 65 thereof, leaving said cover unfolded in the plane of one side wall, and for causing the flaps to fold at right angles to the side walls, some of said elements being stationary and others being movable during the folding operation, (3) mechanism for fastening together the flaps and end walls, after the plunger reaches the final position thereof, (4) means to clamp the bottom section against the advancing plunger, arranged for 75 compelling the finished carton to follow said plunger when the motion thereof is reversed, (5) a device to detach the carton from the returning plunger, and (6) mechanism to move the blank edgewise into position for folding with the cover section at the outer side of the machine.

24. A carton machine for making a square corner carton from a blank having integral bottom and side and end wall sections, and 85 having integral flaps and a cover section integral with one side wall section,—comprising, in combination, (1) a reciprocating plunger, (2) elements coöperating with said plunger to fold the side and end walls of 90 the blank at right angles to the bottom wall thereof, leaving said cover unfolded in the plane of one side wall, and for causing the flaps to fold at right angles to the side walls, some of said elements being stationary and 95 others being movable during the folding operation, (3) mechanism for fastening together the flaps and end walls, after the plunger reaches the final position thereof, (4) means including a reciprocating member 100 having springs to clamp the bottom section against the advancing plunger, arranged for compelling the finished carton to follow said plunger when the motion thereof is reversed, two of said elements 105 consisting of vertical plates arranged to hold the side sections against the plunger, said member reciprocating between the parallel inner surfaces of said plates, and (5) a device to detach the carton from the returning plunger.

25. A carton machine for making a square corner carton from a blank having integral bottom and side and end wall sections, and having integral flaps and a cover section integral with one side wall section,—comprising, in combination, (1) a reciprocating plunger, (2) elements coöperating with said plunger to fold the side and end walls of the blank at right angles to the bottom wall 120 thereof, leaving said cover unfolded in the plane of one side wall, and for causing the flaps to fold at right angles to the side walls, some of said elements being stationary and others being movable during the folding 125 operation, (3) mechanism for fastening together the flaps and end walls, after the plunger reaches the final position thereof,

(4) means to clamp the bottom section against the advancing plunger, arranged for compelling the finished carton to follow said plunger when the motion thereof is reversed, (5) a device to detach the carton from the returning plunger, (6) a shaft in the lower portion of the machine, and (7) means including eccentric cams on said shaft to operate said plunger, and for

actuating said mechanism while said plunger is stationary.

Signed by me at Saint Joseph, Michigan, this 18th day of June, 1909.

EDWARD CRAIG.
